UNITED STATES PATENT OFFICE.

NATHAN H. SUREN, OF NEEDHAM, MASSACHUSETTS, ASSIGNOR TO THE GAMEWELL COMPANY, OF NEWTON UPPER FALLS, MASSACHUSETTS, A CORPORATION OF MASSACHUSETTS.

DESIGN FOR A FACE FOR SIGNAL DEVICES.

Application filed April 13, 1925. Serial No. 13,103. Term of patent 14 years.

To all whom it may concern:

Be it known that I, NATHAN H. SUREN, a citizen of the United States of America, residing at Needham, in the county of Norfolk and Commonwealth of Massachusetts, have invented a new, original, and ornamental Design for Face for Signal Devices, of which the following is a specification, reference being had to the accompanying drawing, forming part thereof.

Figure 1 is a front elevation of the article, showing my new design; and

Fig. 2 is a side elevation thereof.

I claim:

The ornamental design for a face for signal devices, substantially as shown.

NATHAN H. SUREN.
